Primary Examiner—Alan P. Douglas*Assistant Examiner*—Monica A. Hannon*Attorney, Agent, or Firm*—Richard C. Litman[57] **CLAIM**

The ornamental design for a multiple seat rear gate for shopping carts, as shown and described.

DESCRIPTION

FIG. 1 is a front perspective view of a multiple seat rear gate for shopping carts showing my new design;

FIG. 2 is a front, side and top perspective view thereof;

FIG. 3 is a rear, side and top perspective view of a second embodiment thereof;

FIG. 4 is a front, side and top perspective view of the second embodiment thereof;

FIG. 5 is a left side elevational view of the first embodiment thereof, the right side elevational view being a mirror image;

FIG. 6 is a top plan view of the first embodiment thereof;

FIG. 7 is a left side elevational view of the second embodiment thereof, the right side elevational view being a mirror image; and,

FIG. 8 is a top plan view of the second embodiment thereof.

The broken lines in the various drawing figures represent a child, accessory and portions of a shopping cart and form no part of the claimed design.

FIG. 5

FIG. 7

FIG. 6

FIG. 8
